UNITED STATES PATENT OFFICE.

ANDREW RITTER, JR., OF CHICAGO, ILLINOIS, ASSIGNOR OF TWO-THIRDS
TO A. F. NOBLE AND JAMES C. POLLOCK, BOTH OF SAME PLACE.

STEAM-BOILER FURNACE.

SPECIFICATION forming part of Letters Patent No. 290,270, dated December 18, 1883.

Application filed September 3, 1883. (No model.)

To all whom it may concern:

Be it known that I, ANDREW RITTER, Jr., a citizen of the United States, and a resident of Chicago, in the county of Cook and State 5 of Illinois, have invented certain new and useful Improvements in Steam-Boiler and other Furnaces; and I do hereby declare the following to be a full, clear, and exact description of the same, reference being had to the accompanying drawings, forming a part of this 10 specification.

My invention relates to improvements that are more especially adapted to that class of furnaces in which the fire-chamber is arranged 15 at either the front or side of the boiler or other chamber in order to permit of the ready and convenient feeding of the same through openings in the arch of the fire-chamber, and to attain a more perfect combustion of the fuel; 20 and my improvement has for its objects, first, to provide means for heating the air-supply and distributing it in an even manner through the fire-chamber, so as to aid in the thorough and perfect combustion of the gaseous 25 products of the fuel; second, to afford means to prevent excessive radiation of heat from the furnace into the furnace-room, and at the same time utilize the heat which would otherwise be lost by radiation to heat a supply 30 of air used to assist in promoting the combustion of the fuel; third, to furnish an improved construction whereby the fuel can be readily and conveniently fed to the furnace, the escape of smoke and gases into the room 35 prevented, and the draft, to a measure, promoted and regulated. I attain such objects by the construction and arrangement of parts illustrated in the accompanying drawings, in which—

40 Figure 1 is a longitudinal section of a horizontal steam-boiler furnace to which my improvements are applied; Fig. 2, a front elevation of the same, partly in section; Fig. 3, an enlarged horizontal section through the arch of the furnace-chamber; Fig. 4, an enlarged detail view of the grates, and Fig. 5 an enlarged detail view of the hinged drop-plate at the rear of the furnace-grate.

The furnace, as usually constructed, consists 50 of a fire-chamber, A, having a central hori-

zontal grate, B, and inclined side grate, C, on which the fuel is fed through feed pockets or chutes D in the arched top E of the furnace.

In order to feed the fuel down onto the 55 central grate, B, from the inclined grates C, I form such grates so that they will oscillate or rock. My preferred form of rocking grate for this purpose is shown in Fig. 5, yet any other style of rocking grate may be employed 60 without departing from the spirit of my invention. By this means the fuel can be evenly and perfectly fed down onto the central grate without necessitating "stoking" of the fire 65 through the ordinary front fire-door of the furnace.

F is the front plate of the furnace, arranged at a short distance from the furnace-wall proper, so as to form an air chamber or space, as shown, the purpose of this construction being to prevent radiation of heat from the furnace-wall into the furnace-room by causing a circulation of air in the space or chamber, the air-supply being taken in through openings f and discharged into the fire-chamber, 70 to promote combustion, through the flues or passages G G', in the furnace-arch, as shown in Figs. 1 and 3. The horizontal flues or passages G are of varying lengths, and discharge at different points into the furnace-chamber, 75 through short downwardly-inclined ducts or passages, so as to furnish an even supply of air to all parts of the same, and thereby effect a more perfect combustion of the gaseous products of the fuel. A portion, G', of the 80 horizontal flues G do not communicate with the air-heating chamber at the front of the fire-chamber, but take their supply of air from over the arch, through upwardly-inclined ducts or passages g, so as to take air from 85 such point and absorb most of the heat radiated therefrom.

d are vertical air-feeding flues or apertures formed in the division between the feeding pockets or chutes, the purpose of which is to 90 carry a supply of air into the fire-chamber when the supply of air through the pockets D is interfered with or prevented by the filling up of the same with small fuel.

H are air supplying and heating flues or passages formed in the side walls of the furnace, 100

which take their supply of air through the front of the furnace and discharge it through small cross flues or passages into the fuel-pockets D. By means of the flues d and H, a sufficient supply of air is furnished to the fire-chamber, so that there will be no necessity of an air-supply through the pockets, and consequently the doors or covers d' of the same can be kept closed at all times, except when feeding fuel into the pockets. By this means any liability of smoke or gases escaping into the furnace-room is entirely overcome. This construction has the further advantage of preventing any undue heating of the doors or covers d', and the consequent warping and cracking of the same, and is especially valuable where the furnace is lightly fired, as it obviates the necessity of using the doors d' to regulate the draft.

In practical use the various air-supplying flues or passages will be provided with regulating dampers or stoppers, so as to enable the operator to control the supply of air to the furnace or any desired portion of the same.

It is preferred that any retarding of the draft be accomplished by a damper, J, in the breeching or smoke-stack of the boiler.

I is a removable metal arch-plate placed over the furnace-arch, the purpose of which is twofold: first, to form a con-conducting air-space over the furnace-arch; and, second, to form, when turned upside down, a protecting-trough for the top of the furnace in clearing out or washing the boiler.

With the improved furnace, as shown, there is a double draft through the furnace, which at times tends to cause a "backing" up of the heat against the ends of the inclined grates, causing them to unduly expand and buckle up.

I have found by practical experience that this defect can be almost entirely obviated by cutting out or forming an offset, e, in the side walls underneath the grates, as clearly indicated in Fig. 2.

K is a perforated drop-plate hinged in the bearing-bars of the central grate and arranged directly behind the same, the purpose of which is to permit of the cleaning of the fire through the rear of the furnace, toward which the clinkers naturally form, and in the removal of which, by the means stated, does not require the green coal at the front of the furnace to be disturbed, as would be the case in cleaning in the usual way through the front door of the furnace. The drop-plate is manipulated by means of a lever, k, at the front of the furnace, although the connecting-rod k', extends to the arm k' of the drop-plate, as clearly indicated in Figs. 2 and 5.

While it is preferable to arrange the furnace or fire chamber directly in front of the boiler and longitudinally parallel therewith, yet in some cases it may be more convenient to place it at the side of the boiler, or at an angle thereto, or, if absolutely necessary, directly under the boiler, either of which arrangements, as found most convenient or nec-

essary, may be employed without departing from the spirit of my invention.

In the drawings I have shown the central 7c grate as being capable of a rocking motion, so as to clear the fire by rocking the same; yet the ordinary fixed grate-bar may be employed instead, and the usual mode of cleaning the fire by poking the same may be re-sorted to.

I am aware that prior to my invention furnaces have had their walls formed with air-heating ducts or passages for heating a supply of air to promote combustion. I therefore 80 do not claim such provision, broadly.

I am also aware that the front walls and furnace arch or top have been formed with passages or chambers to prevent the radiation of heat from the furnace, and that the arched 85 top of furnaces have been provided with a fixed arch plate or cover of metal, to protect the same and to form an air-chamber to prevent radiation.

What I do claim as my invention, and desire to secure by Letters Patent, is—

1. In a steam-boiler furnace, the fire-chamber A, having an arched top and provided with a central grate, B, inclined side grates, C, and side fuel-feeding pockets, D, in combination with the air-heating passages H, discharging into the fuel-pockets, as described, and for the purpose set forth.

2. In a boiler-furnace, the fire-chamber A, having an arched top and provided with a central grate, B, inclined side grates, C, and side fuel-feeding pockets, D, in combination with the vertical air-supply flue d, formed in the partition between the pockets D, as described, and for the purpose set forth.

3. In a boiler-furnace, the fire-chamber A, having an arched top and provided with a central grate, B, inclined side grates, C, and side fuel-feeding pockets, D, in combination with the air-heating passages H, formed in the 110 furnace side walls, and vertical flue or passage d, as described, and for the purpose set forth.

4. In a boiler-furnace, the fire-chamber A, having an arched top, fire-grates B C, and fuel-feeding pockets D, in combination with air-heating passages G, of varying lengths, formed in the furnace-arch and discharging through short ducts down into the fire-chamber, as described, and for the purpose set 120 forth.

5. In a furnace, the combination of the following elements: the air space or passage formed in front of the front wall of the furnace by plate F, and the horizontal heating-flues G, communicating with said air space or passage and the interior of the fire-chamber, as described, and for the purpose set forth.

6. The combination, with a furnace, of a series of horizontal heating-flues, G G', formed in the arch of the fire-chamber and having openings into the fire-chamber over the fuel, the supply of air being taken, respectively, from the chamber in front of the furnace and from the

top of the furnace through small ducts *g*, substantially as described, and for the purpose set forth.

7. The combination, with a steam-boiler furnace in which the fire-chamber is arranged to the front of the boiler, of the curved plate *I*, arranged to form an air-conduit, and made removable and adapted to be reversed to form a receiving-trough, to protect the top of the fire-chamber in cleaning the boiler, all essentially as herein described.

8. The combination, in a boiler-furnace, of the fuel-feeding pockets *D*, inclined side grates, *CC*, horizontal central grate, *B*, and drop-plate or grate *K*, arranged at the rear of the grate *B*, as described, and for the purpose set forth.

In testimony whereof I have hereunto set my hand this 30th day of August, A. D. 1883.

ANDREW RITTER, JR.

In presence of—

A. F. NOBLE,
H. D. SMALLEY.
